UNITED STATES PATENT OFFICE

CHARLES C. HUFF, OF CLARKS, NEBRASKA

SHARPENER FOR DISK HARROWS

Application filed April 25, 1928. Serial No. 272,668.

This invention relates to sharpeners for disk harrows, and constitutes an improvement upon the subject matter of my Patent Number 1,443,132, issued to me under date of January 23, 1923. The object of the invention is to simplify and otherwise improve the structure described in the said patent, and so as to provide a practical and efficient tool for the sharpening of the disks of such harrows.

In the drawing.

Figure 1 is a side elevation of the device as operatively mounted upon the disk of a disk harrow, a portion of the disk being broken away;

Figure 2 is a view on the line 2—2 of Figure 1, the disk being shown partly in section and partly broken away;

Figure 3 is an enlarged detail in plan of the rod carriers;

Figure 4 is an enlarged detail of the anvil and a portion of the anvil lever formed integrally therewith;

Figure 5 is an enlarged detail in elevation of the upper portions of the anvil and sharpener levers, the connecting adjustment screw with the adjustment wheel in reversed position as required for truing up the edge of the disk, and the retaining spring, the upper extremity of the anvil lever being shown in section.

The invention comprises a frame made up of two pairs of rods, a pair of push rods 1 made by bending a length of rod upon itself, with the bight 2 thereof curved inwardly and so adapted to seat upon the hub 3 of the disk 4, at the convex side of the disk, and a pair of draw rods 5, having the bight 6 thereof inset at 7 and curved outwardly and so adapted to pass underneath the axle 8 of the harrow 9, at the concave side of the disk. The lower portions of the pair of rods 5 are passed through a supporting block 10. Owing to the greater diameter of the hub 3 over the axle 8, the rods 1 are spaced farther apart than the rods 5. Two rod carriers 11 having rod engaging apertures 12 through their extremities and adjustably connected in spaced relation by means of an adjustment or set screw 13, are slidably mounted over the upper free ends of

the rods 1 and 5, two of the extremities of the carriers 11 being turned outwardly at 14 for this purpose. Two set screws 15 passed into two of the apertures 12 afford means for locking the carriers in any adjusted position upon the rods 1 and 5. Curved anvil and sharpener levers 16 and 17 are mounted between the carriers 11 and are pivotally connected by means of a pin 18 passed through the forked extremity of the sharpener lever 17 set 60 astraddle the anvil lever 16 at a lower medial point, and through the said medial point of the anvil lever. The lower and inwardly turned extremity of the said anvil lever carries the integrally formed anvil block 19. 65

The sharpener lever 17 is slotted at 20 and the screw 13 is passed through that slot, whereby the levers are adjustably supported in operative position. The upper extremity of the sharpener lever 17 is formed as shown 70 at 21 and an adjustment screw 22 is hingedly mounted by one end within said forked end by means of a pin 23, the opposite end of the screw being passed loosely through the upper extremity 27 of the opposed anvil lever 16. 75

An adjustment wheel 24 having an offset hub 25 is mounted upon the screw 22 in threaded engagement therewith. An expanding coil spring 26 is mounted over the screw 22 and braced between the wheel 24 and the extremity 27 of the lever 16. A retaining spring 28 is stretched between the points 29 and 30 of the levers 16 and 17, thereby tending to draw together the upper ends of the said levers. A downwardly extending offset 31 from the lever 17 is apertured out to form a tool receiving recess 32 into which a grinding tool 33 is releasably secured by means of the set screw 34. This tool 33 is to be directly aligned with the anvil block 19, and the two are adapted to 85 meet at an angle of inclination from a perpendicular line drawn to the axle 8, corresponding to the inclination of the periphery 35 of the disk 4, to the end that the edge of the disk 4 may be thereby engaged by the tool 33 in 90 just the right way to be rightly sharpened when the said disk is rotated as when being used in the field.

The upper end of the frame as a whole, so formed, may be sustained in operative posi- 100

tion upon the harrow 9 and relative to the disk 4 by means of a bracket 36 extended from the said harrow and provided with holes 37 through which two of the rods 1 and 5 are passed.

5 In use, the device as described is positioned upon the harrow in the manner described, with the edge of the disk to be sharpened placed between the anvil 19 and the tool 33, which adjustment may be readily made by proper manipulation of the wheel 24 and of the lever 17 through the slot 20. Rotation of the disk 4, either by hand or by drawing the harrow over the ground, then results in a 15 sharpening action of the tool 33 upon the edge of the disk. If the disk has an untrue edge, the edge may be trued by merely reversing the wheel 24 upon the screw 22, as shown in Figure 5, and bringing the wheel hub 25 20 to bear directly against the upper end of the lever 16, thereby holding the anvil 19 firmly against the edge 35 of the disk 4, and then revolving the said disk as before. This arrangement will cut off all inequalities of the 25 edge of the disk.

It is understood that I may make any desired minor changes in the structure here shown, not departing from the spirit of my invention as defined in the appended claim.

30 I claim:

A sharpener for disk harrows, comprising a frame made up of a pair of push rods adapted to seat upon the hub of a disk at the convex side thereof and a pair of draw rods 35 adapted for a bearing underneath the axle of the harrow at the concave side of the said disk, two rod carriers slidably mounted one each upon one of the said push rods and one of the said draw rods, the said rod carriers being 40 adjustably connected with an adjustment screw, an anvil lever and a sharpener lever mounted between the said rod carriers, the said levers being pivotally connected, the lower end of the anvil lever carrying an anvil 45 block adapted for positioning laterally at the edge of the disk upon the concave side thereof and the lower offset end of the sharpener lever having means for adjustably supporting a sharpener tool at the edge of the disk upon 50 the convex side thereof and oppositely to the said anvil block, a sharpening stone mounted in the said supporting means at the lower end of the sharpener lever, and means upon the said levers for bringing varying degrees of 55 pressure upon the said levers for forcing the anvil block and sharpening tool together.

In testimony whereof I affix my signature.

CHARLES C. HUFF.
